United States Patent Office

Des. 213,733

Patented Apr. 1, 1969

213,733

MANEUVERING SPACE VEHICLE OR SIMILAR ARTICLE

Loren E. Curriston, La Habra, and Heinz Fornoff, Glendale, Calif., assignors to North American Rockwell Corporation

Filed Aug. 30, 1967, Ser. No. 8,434

Term of patent 14 years

Int. Cl. D12—07

U.S. Cl. D71—1

FIG. 1 is a perspective view of a maneuvering space vehicle or similar article showing our new design; and

FIG. 2 is a perspective view of the opposite sides not shown in FIG. 1.

We claim:

The ornamental design for a maneuvering space vehicle or similar article, as shown.
